GAS OR VAPOUR CONDENSERS

Marcel Jean Pierre Aupex, Paris, France, assignor to Compagnie Francaise Thomson-Houston, Paris, France, a French body corporate

Filed Nov. 18, 1960, Ser. No. 70,250

Claims priority, application France Nov. 26, 1959

5 Claims. (Cl. 230—101)

The present invention relates to condensers for gases and vapours and is a continuation-in-part of my copending application No. 50,481 filed August 18, 1960.

In the aforementioned copending application there is described, particularly with reference to FIGURE 11, an embodiment of condenser particularly for use in diffusion pumps and comprising two spiral baffle devices placed one above the other, in one of which a refrigerant, for example "Freon" circulates, while water circulates in the second device.

Experience has shown that in certain cases in diffusion pumps it is advantageous to mount the two baffles facing in opposite directions, that is to say back-to-back with their bases adjacent each other and their tips respectively one at the top of the chamber in which they are contained and the other towards the lower part of this chamber.

In this case, once the oil being pumped has condensed, instead of being thrown to the circumference of the baffles it goes, on the contrary, back towards the centre.

In order to avoid the effect of counter-diffusion of the vapour arising from the surface of the cap of the upper ejector of the pump, according to the present invention a cover is joined thereto and is mechanically and thermally connected to the geometric tip of the lower baffle.

This cover is made in such a way as to allow the evacuation of the condensed drops of oil through the internal wall of the body of the pump. It is preferably constructed in a similar way to that which has been described in United States patent application No. 65,477 filed by the applicant on October 27, 1960, for "Improvements in Diffusion Pumps," now abandoned.

An embodiment of the invention will now be described with reference to the accompanying drawing which is a view, partly in section, through one construction of apparatus according to this invention.

Referring to the drawing, 1 is the body of the diffusion pump in which is located the ejector 12. This ejector is provided with a cap 13 supported by a rod 14. 2 is the chamber where the two conical spiral baffles 3 and 4 are located, and 5 is the conduit leading to a valve (not shown) and to the chamber to be evacuated. The chamber 2 is secured to the body 1 and to the conduit 5 by joining its edges to the edges of these two members, for example by means of nuts and bolts 6, with the interposition of vacuum-tight joints 7 and 8 of any suitable material. A cover 9 is mechanically fixed by any suitable means and forms a thermal connection to the lower central part or tip of the lower baffle 3.

According to the invention, this cover is constructed in such a way that its lower rim presents a series of projections or points 10 extending downwards, these points being extended by resilient fine wires 11, for example of stainless steel, which are resiliently supported against the internal surface of the wall of the body 1 of the pump.

2

Due to the surface tension of the drops of oil at the points 10, these drops follow the wires 11 and are then evacuated on to the said wall, without the risk of falling back on the pump.

It will be understood that various modifications may be made without departing from the scope of this invention and in particular that this invention may be considered in conjunction with any of the features of my aforementioned copending application No. 50,481.

I claim:

- 10 1. In a diffusion pump having a body in which is located an ejector adapted to be placed in communication with an enclosure to be evacuated, a tubular member mounted on the body and defining a chamber disposed above said ejector, a cover for said ejector located in said body, said cover having a rim formed with projections, wires of a resilient metal extending from said projections and adapted to engage with the body of the pump, and a conical spiral condenser located in said chamber and arranged with its tip directed downwardly and mechanically and thermally connected to the cover.
- 15 2. In a diffusion pump having a body in which is located an ejector adapted to be placed in communication with an enclosure to be evacuated, a tubular member mounted on the body and defining a chamber disposed above said ejector, a cover for said ejector located in said body, said cover having a rim formed with projections, wires extending from said projections and adapted resiliently to engage with the body of the pump, a conical spiral condensing element located in said chamber and arranged with its tip directed downwardly and mechanically and thermally connected to the cover and a further similar conical spiral condensing element surmounting said first-mentioned condensing element and supported by the tubular member and arranged with its tip directed upwardly.
- 20 3. In a diffusion pump having a body in which is located an ejector adapted to be placed in communication with an enclosure to be evacuated, a tubular member mounted on the body and defining a chamber disposed above said ejector, a cover for said ejector located in said body, a conical spiral condenser located in said chamber and supported by said tubular member and arranged with its tip directed downwardly and mechanically and thermally connected to the cover, and a further similar conical spiral condenser arranged above said first-mentioned condenser and supported by said tubular member and having its tip pointing upwards.
- 25 4. Apparatus as claimed in claim 1, in which the wires are made of resilient stainless steel.
- 30 5. In a diffusion pump having a body in which is located an ejector, a cover for said ejector of which the rim is formed with a plurality of projections, wires of a resilient metal extending from said projections and resiliently engaging with the inner surface of the pump body and a condensing element mechanically and thermally connected to said cover for condensing the vapour in said pump.
- 35 6. In a diffusion pump having a body in which is located an ejector, a cover for said ejector of which the rim is formed with a plurality of projections, wires of a resilient metal extending from said projections and resiliently engaging with the inner surface of the pump body and a condensing element mechanically and thermally connected to said cover for condensing the vapour in said pump.
- 40 7. In a diffusion pump having a body in which is located an ejector, a cover for said ejector located in said body, a conical spiral condenser located in said chamber and supported by said tubular member and arranged with its tip directed downwardly and mechanically and thermally connected to the cover and a further similar conical spiral condenser arranged above said first-mentioned condenser and supported by said tubular member and having its tip pointing upwards.
- 45 8. In a diffusion pump having a body in which is located an ejector, a cover for said ejector located in said body, a conical spiral condenser located in said chamber and supported by said tubular member and arranged with its tip directed downwardly and mechanically and thermally connected to the cover, and a further similar conical spiral condenser arranged above said first-mentioned condenser and supported by said tubular member and having its tip pointing upwards.
- 50 9. In a diffusion pump having a body in which is located an ejector, a cover for said ejector located in said body, a conical spiral condenser located in said chamber and supported by said tubular member and arranged with its tip directed downwardly and mechanically and thermally connected to the cover and a further similar conical spiral condenser arranged above said first-mentioned condenser and supported by said tubular member and having its tip pointing upwards.
- 55 10. In a diffusion pump having a body in which is located an ejector, a cover for said ejector located in said body, a conical spiral condenser located in said chamber and supported by said tubular member and arranged with its tip directed downwardly and mechanically and thermally connected to the cover and a further similar conical spiral condenser arranged above said first-mentioned condenser and supported by said tubular member and having its tip pointing upwards.
